UNITED STATES PATENT OFFICE.

CHARLES DARGENT, OF BROOKLYN, NEW YORK.

DESIGN FOR A WATER-HEATER.

53,844.

Specification for Design.

Patented Sept. 16, 1919.

Application filed January 31, 1919. Serial No. 274,376. Term of patent 14 years.

To all whom it may concern:

Be it known that I, CHARLES DARGENT, a citizen of the United States, residing at the city of New York, borough of Brooklyn, in the county of Kings and State of New York, have invented a new, original, and ornamental Design for a Water-Heater, of which the following is a specification, reference being had to the accompanying drawing, forming part thereof.

Figure 1 is a side view of a water heater

showing my new design, the said design comprising a hexagonal body terminating in flattened spherical ends and having a cylindrical projection extending from two sides of the hexagonal body.

Fig. 2 is a front view of the heater shown in Fig. 1.

I claim:

The ornamental design for a water heater as shown and described.

CHARLES DARGENT.
